Lucian C. Jackson, Buffalo, N. Y.

Application March 22, 1940, Serial No. 325,409

4 Claims. (Cl. 81—60)

My invention relates to wrenches and more particularly to a ratchet wrench in which the ratchet pin operates the nut turning member, or socket, continuously in one direction so that a nut can be tightened by using one side of the wrench and loosened by using the other side of said wrench.

One of the objects is to provide a wrench of this type which will be simple in arrangement and structure to be produced at a comparatively low cost.

Another object is to provide a ratchet mechanism which is strong and durable and which will operate with a minimum of friction when running free.

Another object is to provide a wrench with improved means for retaining the socket in the head.

With these objects in view, the invention consists in certain features of novelty in the construction, combination and arrangement of parts by which the said objects and certain other objects which will hereinafter appear are attained, the invention being more particularly pointed out in the claims.

In the drawings accompanying and forming a part of this specification:

Figure 1 is a plan of one side of the wrench.

Fig. 2 is a longitudinal section on lines 2—2 of Fig. 3.

Fig. 3 is the upper half of the wrench above line 3—3 of Fig. 2 and showing the socket and ratchet mechanism in position.

Fig. 4 is the head portion of the upper half of my wrench above line 4—4 of Fig. 5 and showing a modified ratchet mechanism and socket in position, the socket being removable.

Fig. 5 is a section on line 5—5 of Fig. 4.

Fig. 6 is a section on line 6—6 of Fig. 3.

Fig. 7 is a section on line 7—7 of Fig. 4.

Fig. 8 is an elevation of the socket shown in Figs. 1, 2 and 3.

Fig. 9 is an elevation of the socket shown in Figs. 4 and 5.

Fig. 10 is a partial section on line 10—10 of Fig. 11 of a modified shape of handle and socket with the ratchet mechanism of Figs. 4 and 5, with the ratchet and socket readily removable.

Fig. 11 is a section on lines 11—11 of Fig. 10.

Fig. 12 is the head portion of the wrench as in Fig. 11 but sectioned on lines 12—12 of Fig. 13 with the ratchet of Figs. 2 and 3 and the socket having a modified locking device.

Fig. 13 is a section on line 13—13 of Fig. 12.

Fig. 14 is a section on line 14—14 of Fig. 15 of the locking ring shown in position in Fig. 11.

Fig. 15 is a plan of the locking ring of Fig. 14.

Fig. 16 is a section on line 16—16 of Fig. 10.

Fig. 17 is a section on line 17—17 of Fig. 13.

My wrench consists essentially of a handle and a head having a circular opening therethrough for holding a nut turning socket which is operated by a ratchet mechanism consisting of a pin and a coiled spring extending into said handle.

As a convenient and inexpensive means of holding the socket and ratchet mechanism I have shown in Figs. 1 to 9 a handle 1 and a head 2 formed from two pieces of suitable material placed together and fastened by means of rivets 3, 3 etc. If it is desirable to change the sockets for different size nuts, screws (as indicated at 3a) can be substituted for the rivets. When the two halves are formed from a metal stamping 15 a convenient means of fastening is to spot weld them together. These halves which are similar in shape, but right and left, are designated as 4 and 5 respectively.

6 is a socket (outside view shown in Fig. 8) 25 rotatably locked in the annular chamber 7 formed by the two halves of the head 2. Each side of the head 2 has a circular opening 8 to form a bearing for the journals 9, 9 of the socket 6. Extending through socket 6 is an opening 10 of suitable shape and size for engaging with a nut. Around the center of the periphery of the socket 6 is a flange 11 in which the ratchet teeth indents 12 are formed. Each ratchet tooth indent 12 has a flat side 13 meeting at right angles with a flat side 14. Flat sides 13 and 14 are adapted to fit the end and side respectively of a ratchet pin 15, square in section as shown in Fig. 6. Bearing against the end of pin 15, opposite the ratchet teeth indents 12, is a coil spring 16 for keeping said pin 15 engaged with said ratchet teeth 12. The pin 15 and spring 16 are contained in a pocket 17 adjacent to the upper edge of the handle 1 (Fig. 3) as a convenient continuation of the oval border 18 which runs around the 30 edge of said handle.

In the ordinary construction, as Womelsdorff, No. 272,822 or Chellis No. 658,618 and as in my patent, Moulthrop et al. No. 1,155,158 the center lines of the handle, the ratchet pin and the 35 wrench head coincide, so that the strain of tightening a nut operates principally to shear off the unsupported end of the pin or to shear off the tooth. Also in the usual construction the ratchet pin is beveled on the end to make it rise out of 40 the tooth indent and this reduction in section 45

weakens said pin at the point of greatest strain and in practice is the cause of most ratchet mechanism failures. This is illustrated by 12 in Fig. 2 of Chellis, No. 658,618 and it will also be noted that the weakest section of his tooth is at the bottom where it should be the strongest.

In my present invention, which is an improvement on my Patent No. 1,155,158 the pin is also of the same size throughout its length. However the pin centerline 19 is not directed toward the center or axis X of the socket 6 but is parallel to, and offset from the centerline 20 of the handle 1 a distance 22, while said handle centerline 20 is offset from the socket center X a distance 21 so that the pin centerline 19 is offset from the socket center X a distance 23. The offsetting of the handle centerline 20 a distance 21 from the socket center is to accommodate the inclosing of the pin 15 within the handle and in this instance is dependent on the offset 23 and the size of said pin 15. The offset distance 23 of the pin centerline 19 from the center X of socket 6 is preferably about as shown, i. e. approximately one-half the distance from the socket center X to the periphery of the ratchet teeth. This offset distance 23 can vary from one-quarter to three-quarters of the radius to the periphery of the ratchet teeth depending on the size of the socket and the ratchet pin. It is desirable that practically the whole upper length of the ratchet pin 15 (Fig. 3), which is opposite to the side 14 of tooth indent 12, have a bearing in the pocket 17 as the thrust from said tooth side 14 will then be backed up by said pocket wall. This gives increased strength to the pin over the pin shown in Patent No. 1,155,158. The offsetting of the ratchet pin as shown provides a strong tooth as the side, or lead, 13 (extended, Figs. 3 and 13) would cut below the root of an adjacent tooth and hence sides 13 and 14 (extended) pass on opposite sides of axis X.

In offsetting the ratchet pin the ratchet mechanism also works much easier than the usual type as the point of the tooth on side 13 presses directly against the end of pin 15 in retracting said pin against its spring 16. In the usual type where the pin has a beveled end, part of the force exerted to retract said pin is absorbed by pressing it against the side of its pocket.

In operating the wrench on a nut, the handle 1 is moved down in the direction of arrow 24 (Fig. 3) when the lower end of pin 15 bearing against side 14 of a tooth indent 12 causes the socket and said nut to turn with the movement of said handle, while reversing the movement the socket is held stationary by the nut and the ratchet runs free, i. e. the pin 15 is retracted to rise out of each tooth indent by the side 13 acting against the end of said pin. When right side 4 of the wrench (Fig. 2) is on a right hand thread nut, said nut will be screwed on to a bolt, while if the left side 5 is on said nut it will be screwed off from said bolt.

In Figs. 4 and 5 the handle 1 has a head 2a in which 8a is a circular transverse opening therethrough to accommodate a socket 6a having ratchet teeth indents 12a with a flat side 13 meeting a side 14a to form a right angle. Fig. 9 shows outside view of socket 6a. Side 14a is semi-circular to fit a cylindrical ratchet pin 15a. Fig. 7 shows section of said pin in pocket 11a. In this construction socket 6a is retained in wrench head 2a by means of the ratchet pin 15a while engaged with ratchet teeth indents 12a or by the curved groove 25, connecting the

teeth indents in the periphery of said socket 6a, while passing between said teeth indents.

The corner of ratchet pin 15a fits the curve of groove 25 in passing from one tooth indent 12a to another and when in this position the socket 6a can be removed from head 2a by side pressure with the hands to force said pin 15a out of groove 25.

Figs. 10 to 17 show a handle 1a and head 2b in one piece, with a pin centerline 19 offset a distance 23 from the socket center X but with the pin centerline 19 crossing the handle centerline 20 at an angle so the pin and spring can be inserted through the side of said handle. 26 15 is a plug screw for the convenient removal of the 15 spring and pin.

Figs. 10 and 11 show the ratchet teeth indents 12a with the flat side 13 and the semi-circular side 14a to fit the end and side of pin 15a respectively. Socket 6b is rotatably mounted in the circular transverse opening 8b and is retained in head 2b by means of a flange 27 on one side and a snap ring 28 in a groove 29 on the opposite side. Snap ring 28 is shown in detail in Figs. 14 and 15 with the split 30 for springing open to insert ring in groove 29. Fig. 16 is section 16—16 of Fig. 10 and indicates shape of handle 1a and pin 15a.

Socket 6c (Figs. 12 and 13) has ratchet teeth indents 12 with flat sides 13 and 14 which are formed down into its periphery to cooperate with a pin 15 with a square section as in Fig. 17. Socket 6c is retained in head 2b by pin 15 in a tooth indent 12 or by channel sides 31, 31 when passing from one tooth indent to another. Opposite pin 15 is a screw 32 with end 33 which projects into and co-operates with the sides 31, 31 of the channel as additional means of retaining socket 6c in head 2b.

Having thus described my invention, I claim:

1. A wrench with a handle and an annular head, a socket to rotate in said head, one side of said socket used to tighten a nut and the opposite side used to loosen a nut, ratchet teeth formed by indents therebetween in the periphery of said socket, said teeth indents connected by a curved depression in said periphery, a cylindrical ratchet pin of uniform section throughout its length and a spring, said ratchet teeth indents formed by two surfaces meeting at right angles to fit the side and end of said pin, said pin directed away from the axis of said socket and cooperating with the said curved depression in the periphery of said socket to yieldingly hold said socket in the head and whereby said socket may be removed from said head by lateral pressure to retract said pin.

2. A wrench with a handle and a head, a nut-turning socket for said head, ratchet teeth indents formed in the periphery of said socket, said teeth indents connected by a curved depression in said periphery, a cylindrical ratchet pin of uniform section throughout its length to cooperate with said indents and said curved depression, a spring to cooperate with said pin, said teeth indents formed by two surfaces meeting at an angle to fit the curved side and flat end of said pin, said pin directed away from the axis of said socket, said socket having marginal annular flanges projecting outwardly of the teeth and a screw to cooperate with the said depression in said periphery between and engaged with said flanges for holding the socket in the head.

3. A wrench with a handle and an annular head, a nut turning member, one end of which

will tighten a nut and the opposite end of which will loosen a nut, ratchet teeth formed by indents therebetween in the periphery of said member, an enclosed ratchet mechanism consisting of a spring and a cylindrical pin to cooperate with said ratchet teeth, said pin being operative on any side and directed away from the axis of said member, a curved groove connecting the indents between said teeth as a guide to yieldingly hold said member in the socket by the corner of said pin, whereby said socket may be removed from said head by lateral pressure to retract said pin.

4. A wrench with a handle and a head, said head having a transverse opening therethrough as a bearing for a socket, a socket, one end of which will tighten a nut and the opposite end of which will loosen a nut, said socket having a

cylindrical surface for bearing in said head transverse opening, ratchet teeth indents formed below said cylindrical surface by the meeting of two faces at an angle, said faces consisting of a flat lead and a curved driving face, an enclosed ratchet mechanism including a spring and a pin, said pin being of a uniform cylindrical shape with squared ends to cooperate with said teeth and directed away from the axis of said socket, and means to hold said socket in said head comprising a curved groove connecting said teeth indents to cooperate with said pin in passing between said teeth indents, whereby said socket is yieldingly held in said head by said pin and groove and can be dismounted from said head by lateral pressure to retract said pin.

LUCIAN C. JACKSON.
